UNITED STATES PATENT OFFICE.

ALEXANDER EISEMANN, OF NEW YORK, N. Y.

RECONSTRUCTED PLUME.

1,032,364.

Specification of Letters Patent.

Patented July 9, 1912.

Application filed June 9, 1911. Serial No. 632,102.

To all whom it may concern:

Be it known that I, ALEXANDER EISEMANN, a citizen of the United States, and a resident of the city, county, and State of 5 New York, have invented certain new and useful Improvements in Reconstructed Plumes, of which the following is a specification.

This invention relates to plumes, with 10 particular reference to what are known in the feather trade as "imitation" ostrich plumes, or doubtless more properly, reconstructed plumes, in view of the fact that a so-called "imitation" plume means two or 15 more smaller feathers so secured together as to have the appearance of a single feather of larger size. It is well known that a larger, more ornamental and consequently more popular plume of this character, if a single 20 feather, is comparatively very expensive, and it has been the practice to secure together a number of smaller and comparatively cheap feathers in such a manner as to have the appearance of a larger and more 25 ornate plume, the cost of the required number of smaller feathers being much less than the cost of a single feather of the desired size.

The principal object of the present invention is the production of such a reconstructed plume from two or more smaller feathers in such manner as to provide the largest and most ornamental plume from the smallest 35 number of feathers, and at the same time improve and simplify the construction and cheapen the cost of manufacture.

My invention will be more readily understood by reference to the accompanying drawings, forming a part of this specification, in which—

Figure 1 is a rear view of a reconstructed plume embodying my invention; Fig. 2 is a front view of the same in a partially constructed state, and Fig. 3 is a front view of 45 the completed plume.

Referring now to the drawings in detail, numeral 5 refers to foundation of more or less flexible material, such as cape-net, although buckram is also a desirable material 50 for this purpose. This foundation 5 is cut or formed to the desired shape, probably best described as "flattened egg-shaped," substantially as shown on Figs. 1 and 2, this shape being that which determines the shape 55 of the finished plume. If this foundation 5 is of woven fabric, such as the cape-net re-

ferred to, the edges thereof are preferably hemmed to prevent fraying and to provide substantial yet flexible support for the flues which are secured thereto in the manner hereinafter described. I then take a comparatively small and inexpensive feather and "strip" the flues from the quill. This operation, as is well known, is that of peeling the skin, with the flues attached thereto, 60 from the fatty or woody core of the quill. This leaves the flues in their natural order and arrangement on a strip of this skin, which is then cut longitudinally to divide the feather into halves 6 and 7. One or 65 more of these halves are then sewed or otherwise secured through the strip of skin to the edge of each side of the foundation 5, as shown in Fig. 2. Obviously, a less effective plume may be provided by securing a 70 single half of a stripped feather along the edge of the foundation, although two or even more are preferable. I now take another comparatively small feather 8, large 75 enough, however, to completely cover the foundation 5, lay the same in symmetrical disposition over said foundation and secure the quill 9 of said feather thereto. If this foundation is of fabric, as shown, the quill 9 may be so secured by stitches at intervals 80 along the length of the quill. The flues of this feather 8, while they do not extend laterally to the edge of the finished plume, entirely cover the upper face of the fabric strip or other foundation, projecting a 85 greater or less distance over the flues secured to the edges of said foundation. In this manner, it will be apparent that the top or exposed side of the plume will present the appearance of a single feather larger and 90 more ornate than any of those of which it is constructed. The reconstructed plume may be made more or less ornate according to the 95 number of stripped feather halves secured in superposed arrangement to the edges of the 100 foundation.

I claim as new and desire to secure by Letters Patent:

1. A reconstructed plume comprising a flexible foundation of proper shape, a row 105 of flues stripped from a natural feather secured along the edges of said foundation, and a feather secured to and symmetrically covering said foundation, substantially as shown and described.

2. A reconstructed plume comprising a flexible foundation of proper shape, a

stripped feather being suitably secured along each side edge thereof with the flues projecting outwardly therefrom and a feather secured to and symmetrically covering said foundation, the flues of said feather projecting over a portion of said first-mentioned flues, substantially as shown and described.

3. A reconstructed plume comprising a flexible foundation of fabric or the like cut to proper shape, a row of flues stripped from a natural feather secured along the edges of said foundation and projecting outwardly therefrom, and a feather secured through its quill to said foundation to symmetrically cover and conceal the latter, substantially as shown and described.

4. A reconstructed plume comprising a flexible foundation of fabric or the like cut to proper shape, one of the side halves of a stripped feather being suitably secured along each side edge thereof with the flues projecting outwardly therefrom, and a

feather secured through its quill to said foundation to symmetrically cover and conceal the latter, substantially as shown and described.

5. A reconstructed plume comprising a flexible foundation of fabric or the like cut to proper shape, one of the side halves of a stripped feather being secured through the skin of its quill to each side edge of said foundation with the flues projecting outwardly therefrom, and a feather secured through its quill to said foundation to symmetrically cover and conceal the latter, the flues thereof projecting over a portion of said first-mentioned flues, substantially as shown and described.

In testimony of the foregoing, I have hereunto set my hand in the presence of two witnesses.

ALEXANDER EISEMANN.
